1,962,154

MAGNETOSTRICTIVE VIBRATOR

George W. Pierce, Cambridge, Mass.

Application April 23, 1928, Serial No. 272,032
In Canada December 31, 1927

3 Claims. (Cl. 250—36)

The present invention relates to electrical systems and apparatus, and more particularly to systems and apparatus for producing and sustaining electric, magnetic and mechanical oscillations. From a more limited aspect, the invention relates to the frequency control and the frequency stabilization of the electric oscillations of electric circuits, and to the transfer of periodic, electric energy from one electric system to another.

The chief object of the present invention is to provide novel oscillators and oscillating systems embodying magnetostrictive vibrators.

Other objects will be explained hereinafter and will be particularly pointed out in the appended claims, it being understood that it is intended to set forth, by suitable expression in the claims, all the novelty that the invention may possess.

20 In the accompanying drawing, Fig. 1 is a diagrammatic view of a novel oscillating system according to the present invention; and Fig. 2 is a similar view of a modification.

A magnetostrictive core 2 is shown axially positioned within an inductive and resistive field coil, indicated in the figures by the numerals 10, 22 and 24. The core 2 may be in the form of a tube, or a rod, or it may be otherwise constructed. It is preferably of nickel, nickel-steel, nickel-copper, nickel-cobalt, chrome-nickel, chrome-steel, or of any other metal element or alloy characterized by comparatively large magnetostrictive effects. By proper choice of length and other dimensions, the apparatus is applicable to systems 35 of high or low frequency within a range that may extend from a hundred cycles to hundreds of thousands of cycles.

The core 2 may freely rest centrally upon a support 6, or it may be centrally clamped between 40 the support 6 and a second clamping member 8, as illustrated in Fig. 1, or it may be otherwise supported. When an electric current is passed through the coil, a magnetic field will be established that will cause very slight mechanical distortion or deformation of the core 2 by magnetostriction. The resulting increment of deformation may be a lengthening or a shortening, or some other distortion, depending on the material and on the polarity of the increment of the magnetic field. This action of the magnetic field upon the core 2 will, for brevity, be hereinafter termed 50 "stimulation". Conversely, any mechanical deformation or distortion of the core will cause a magnetostrictive reaction upon the electromagnetic field, and this will have its effect upon the

electric current or voltage in the coil. The increment of magnetization depends upon the nature of the preexisting magnetic field and the mechanical deformation. This reaction will, for brevity, be hereinafter referred to in the specification and the claims as the "response".

If the current or voltage is alternating, the electromagnetic field created thereby will also be alternating. The core 2 will, therefore, increase and decrease in length (let us say) many times a second, every variation in the current producing its stimulative effect on the core 2 and every deformation of the core producing its reaction response upon the current. The core 2 will, in consequence, freely vibrate mechanically by magnetostriction about a nodal point at its center with a period of vibration equal to the period of the alternating electromotive force. Ordinarily, these vibrations will be quite small. When the alternating frequency is close to, or substantially 75 the same as, the natural frequency of mechanical vibration of the core 2, however, the amplitude of vibration of the core, though still small, becomes relatively quite large. The core will then react inductively on the load to render its 80 consumption of power critical as to frequency for frequencies near the free frequency of the core. The mechanical damping of the core, mounted as shown, is as small as possible, with the result that the resonant response of the core is very 85 sharp and pronounced. Of course, there will usually be more than one specific frequency of magnetization at which the core will thus resonate; for, in addition to one or more natural 90 fundamental frequencies of mechanical vibration, it has also frequencies of vibration determined by the operation of the core in halves, thirds, fourths, fifths, etc. The theory of this 95 operation is explained more at length in Letters Patent No. 1,750,124, granted March 11, 1930, and it will be sufficient here to remember that the operation described herein is equally applicable to the fundamentals and to their overtones.

According to a feature of the present invention, the movements of the magnetostrictive device may be employed to effect the modulation of a local current. The modulations of the local current may be utilized to send current back through the coil so as to produce sustained oscillations, with a constant frequency determined by 100 the natural period of one of the modes of mechanical vibration of the core. One such novel oscillating system is illustrated in Fig. 1. The core 2 is held axially of a magnetic field produced by coils 22 and 24 by means of the centrally 105

110

positioned clamps 6 and 8, so as freely to vibrate longitudinally about a nodal point at its center. For symmetry, one of the coils is positioned on one side of the middle of the core 2 and the other on the other side. The coils may be compacted near the center of the rod, or they may be separated or spread out, each over the whole region of the half-length of the rod, or they may be replaced by a single coil. The field coils 22 and 24 of the oscillator are connected, in series with a local battery 18, between the filament 26 and the plate 28, in the output or plate circuit of a vacuum tube 30. A winding 67 is connected between the grid 32 and the filament 26 of the tube. The winding 67 is coupled to a winding 69 that is connected in circuit with a microphone 71 attached to the support 6. The core is driven by the coils 22 and 24. The transverse vibration of the core 2, being communicated to the supports 6 and 8, will cause variations in the electrical conductivity of the microphone 71. The circuit of the winding 69 comprises, in addition to the microphone 71 and the support 6, the support 8 and a battery 73. A tuning condenser, not shown, may be shunted about one or both of the coils 22, 24.

The theory of the oscillator of Fig. 1 is probably somewhat as follows: Fortuitous variations of plate current effect magnetization of the magnetostrictive core, and the latter becomes magnetostrictively deformed, and the core is started in vibration. These vibrations are transmitted to the supports 6 and 8, causing changes in the electrical conductivity of the microphone 71. Variable electromotive forces are thus generated in the winding 67 through the winding 69. With proper polarity of the transformer, this varies the current in the coils 22 and 24, varying the stimulation of the core. The core then causes further electrical changes in the winding 69, and so on. The local current of the battery 73, sent through the microphone 71, becomes thus modulated in accordance with the current of the battery 18 and acts inductively on the grid-filament circuit 26, 32, 67 of the tube 30. The system will oscillate at a frequency determined by the frequency of mechanical vibration of the rod.

It is not essential that a vacuum tube be employed in order to produce oscillations. In the system of Fig. 2, the winding 75, in the local circuit with the microphones 15, 17, and the battery 11, is coupled to a winding 77 in a secondary circuit with the coil 10 and the tuning condenser 13. The energy of the battery 11 in the local circuit is thus transmitted inductively through the windings 75 and 77 to the driving coil 10, and the energy is fed back magnetostriictively to the coil 75, and so on. The system thus drives itself, and here, again, the frequency of the oscillations is substantially constant and equal to the natural frequency of mechanical vibration of the core.

One of the important characteristics of this invention is that the core 2 may itself be a tuned element of very low decrement, so as to dispense with or supplement electrical tuning of the circuits. Greater sensitiveness and selectivity may,

however, be obtained by electrically tuning the signal circuits in any well known way. The local adjustable condenser 13 in the secondary circuit enhances the operation.

Of course, the microphones 15, 17, one or both, and the microphone 71, may be replaced by any other variable-resistance or variable-contact devices, or by any equivalent device for varying the electrical conductivity in response to mechanical deformations of the core, and preferably attached to, or forming part of, the core 2. In particular, the core itself may be an element of variable resistance.

The magnetostrictive core may either be permanently magnetized, or it may be magnetized electromagnetically from a local source, as by the batteries 18 and 81. The battery 81 further supplies the field winding 10 of the oscillator with direct current through a choke coil 83.

The oscillator may, of course, be used to supply a load 85, either directly, or through tuned circuits. This may be effected by taking off the power developed in the oscillator inductively by a coil 87, through a transformer 89.

The invention is not, of course, limited to the modifications illustrated herein, and may be further modified and changed by persons skilled in the art without departing from its spirit and scope, as defined in the appended claims.

What is claimed is:

1. An oscillatory system comprising a coil, a winding in circuit therewith, and a magnetomechanical vibrator energized by the coil, the vibrator being adapted to vibrate mechanically by magnetostriction, means cooperatively related to the vibrator so that its electrical conductivity varies in accordance with the magnetostrictive deformations of the vibrator, means connecting the first-named means in an electric circuit, a source of energy for the circuit, and a winding in the circuit coupled to the first-named winding.

2. An electric system having, in combination, two circuits each having a coil, a source of energy for one of the circuits, the coils being coupled together, a magnetostrictive body, means connected in one of the circuits and cooperatively related to the body so that its electrical conductivity varies in accordance with the magnetostrictive deformations of the body, the other circuit having an energizing coil for the magnetostrictive body, whereby energy is transferred from one circuit to the other, a further coil in inductive relation to the energizing coil, and a load circuit electrically connected to the last-named coil.

3. An electric system having, in combination, two circuits each having, a coil, a source of energy for one of the circuits, the coils being coupled together, a magnetostrictive body, and means connected in one of the circuits and cooperatively related to the body so that its electrical conductivity varies in accordance with the magnetostrictive deformations of the body, the other circuit having an energizing coil for the magnetostrictive body, whereby energy is transferred from one circuit to the other circuit.

GEORGE W. PIERCE.
